UNITED STATES PATENT OFFICE.

WILLIAM JAMES ROGERS, OF PLAINFIELD, NEW JERSEY.

NEEDLE-THREADER.

1,008,731.

Specification of Letters Patent. Patented Nov. 14, 1911.

Application filed September 17, 1910. Serial No. 582,535.

To all whom it may concern:

Be it known that I, WILLIAM JAMES ROGERS, a citizen of the United States, and a resident of Plainfield, in the county of Union and State of New Jersey, have invented a new and Improved Needle-Threader, of which the following is a full, clear, and exact description.

My invention relates to needle threaders, and it has for its object to provide one having a handle, with a guideway in which a member carrying a plunger is adapted to travel, a member carrying a thread catcher being pivoted to the handle, and having means for reciprocating the member carrying the plunger.

Another object of my invention is to provide a spacing arm adjustably mounted on the handle adapted to abut against the bottom of a needle bar for holding the plunger in alinement with the eye of a needle.

Still other objects of the invention will appear in the following specification, in which the preferred form of my invention is disclosed.

In the drawings, similar characters of reference indicate corresponding parts in all the views, in which—

Figure 1 is a perspective view of my invention, shown in position for service; Fig. 2 is a sectional view on the line 2—2 of Fig. 3; Fig. 3 is a sectional view on the line 3—3 of Fig. 2; Fig. 4 is a plan view of the device; and Fig. 5 is an end view of the device.

By referring to the drawings it will be seen that a handle 5 is provided, having a transverse slot 6, which serves as a guideway, and which is connected with a vertical slot 7, extending through a terminal of the handle. A member 8 is mounted for traveling in the horizontal transverse slot 6, this member 8 being provided with projecting end members 9, which prevent the member 8 from becoming displaced laterally, while permitting the said member 8 to move longitudinally freely in the said slot 6. There is also secured to this member 8, a laterally extending arm 10, having a recess 11 and to the outer end of the member 8, there is secured a plunger 12, adapted to move outwardly in the vertical slot 7.

Pivoted to flanges 13 on the handle 5, there is a member 14, the central portion of which is disposed in the horizontal slot 6, below the member 8. This member 14 has lateral wings 15, which may be engaged by

the fingers of the operator to move it relatively to the handle, a pin 16 being mounted on one of these wings 15, this pin 16 being disposed in the recess 11 on the arm 10, of the member 8. This member 14 also has a forwardly projecting portion 17, carrying a slotted arm 18, adapted to travel back and forth across the end of the handle having the vertical slot 7. A hook 19 is secured to one of the members of the slotted arm 18, the hook 19 being disposed between the two members forming the said slotted arm. A spacing arm 20 is pivoted to the handle 5 at 21, there being a slot 22 in this spacing arm 20, in which is disposed a screw 23, which meshes in a threaded orifice in the handle 5. This spacing arm 20 has a horizontal flange 24, having a vertical slot 25.

In using the device the spacing arm 20 is adjusted by means of the screw 23, so that when the needle 26 is disposed in the vertical slot 25, and the horizontal flange 24 is disposed against the bottom of the needle bar 27, the plunger 12 will be disposed on a plane with the eye 28 of the needle 26. This having been done the thread 29 is disposed in the vertical slot 7, and the handle 5 is moved so that the plunger 12 will be disposed in the direction of the eye 28 of the needle 26. This having been done, the operator moves the member 14, by means of the lateral wings 15, so that the slotted arm 18 will move across the end of the handle having the slot 7. As this is done, the pin 16 which is disposed in the recess 11 moves the arm 10, so that the member 8 is thrust forwardly and the plunger 12 engages the thread 29 so that the plunger 12 thrusts the thread 29 through the eye 28 of the needle 26. The hook 19 on the slotted arm 18 catches the thread 29 as the arm 18 is moved to the right, thereby holding the end of the thread through the eye 28 of the needle 26, as the plunger 12 is withdrawn therefrom.

Having thus described my invention I claim as new and desire to secure by Letters Patent:

1. In a needle threader a handle having a guideway, a member carrying a plunger mounted for moving in the guideway, a member pivoted to the handle having means for moving the first-mentioned member in the guideway, and an arm having a hook for catching the thread mounted rigidly on the second-mentioned member.
2. In a needle threader a handle having a

guideway, a member carrying a plunger mounted for moving in the guideway, a member pivoted to the handle and having means for moving the first-mentioned member in the guideway, an arm mounted on the second-mentioned member for moving therewith in the same plane, and a hook mounted on the arm for catching the thread.

3. In a needle threader a member having a guideway, a second member having a plunger for traveling in the guideway, a slotted arm adapted to move past the end of the plunger, and a hook secured to the slotted arm for catching the thread.

4. In a needle threader a handle having a guideway and a slotted terminal, a member having an arm and carrying a plunger adapted to travel in the guideway, the plunger being adapted to move outwardly in the slot, a member articulated to the handle having means for engaging the arm for operating the first-mentioned member, a slotted arm mounted on the second-mentioned member adapted to move past the slotted terminal of the handle, and a hook secured to the slotted arm.

5. In a needle threader a handle having a guideway, and a slotted terminal, a member having an arm and carrying a plunger adapted to travel in the guideway, the plunger being adapted to move outwardly in the slot, a member articulated to the handle having means for engaging the arm for operating the first-mentioned member, a thread catcher mounted on the second-mentioned member, and a spacing arm secured to the

handle and adapted to abut against the needle bar of a sewing machine for holding the plunger on a plane with the eye of a needle mounted on the needle bar.

6. In a needle threader a handle having a guideway, a member having a plunger and an arm adapted to move along the guideway, a second member pivoted to the handle having means for engaging the arm for moving the first-mentioned member in the guideway, and an arm having a hook for catching the thread mounted rigidly on the second-mentioned member.

7. In a needle threader a handle having a guideway, a member carrying a plunger mounted in the guideway or moving longitudinally thereof, and a second member pivoted to the handle for moving at right angles to the direction of movement of the plunger, means on the second-mentioned member for operating the first-mentioned member in the guideway, the said means being so disposed that the device may be held and the second mentioned member may be actuated by one hand of the operator, an arm mounted rigidly on the second-mentioned member, and a hook on the arm adapted to move past the end of the plunger.

In testimony whereof I have signed my name to this specification in the presence of two subscribing witnesses.

WILLIAM JAMES ROGERS.
